UNITED STATES PATENT OFFICE.

JOHN HARRY CLEMMENCY, OF PHILADELPHIA, PENNSYLVANIA.

MOTOR-REWINDING DEVICE FOR TALKING MACHINES.

1,152,297.

Specification of Letters Patent. Patented Aug. 31, 1915.

Application filed May 26, 1914. Serial No. 341,133.

To all whom it may concern:

Be it known that I, JOHN HARRY CLEMMENCY, a citizen of the United States, residing at Philadelphia, in the county of Philadelphia and State of Pennsylvania, have invented new and useful Improvements in Motor-Rewinding Devices for Talking-Machines, of which the following is a specification.

16 The invention relates to music and more particularly to talking machines, and phonographs, and has for an object to provide a machine in which the mechanism and sounding horn are contained in a suitable casing 15 or box normally closed by a lid which, when actuated, will wind up the usual spring motor for use in imparting rotation to the record to produce the desired sounds and music.

20 The invention contemplates, among other features, the provision of a closure for the box-like body of the machine and which can be automatically opened, said closure when returned to closed position being 25 adapted to wind up the motor which operates the record.

To this end the invention contemplates suitable mechanism having connection with the spring motor and the cover whereby 30 when the cover is closed the spring motor will be wound up, said mechanism also including suitable means whereby the cover will be swung into an open position when the same is released from its normal closed 35 position on the box-like body or casing.

In the further disclosure of the invention reference is to be had to the accompanying drawings, constituting a part of this specification, in which similar characters of reference denote corresponding parts in all the views, and in which:

Figure 1 is a fragmentary side elevation of a talking machine with a portion of the side broken away to disclose the underlying structure; Fig. 2 is a plan view, the cover having been broken away; Fig. 3 is a vertical sectional view taken on the line 3—3 looking in the direction of the arrow; Fig. 4 is a vertical transverse sectional view taken 45 on the line 4—4 in Fig. 2; Fig. 5 is a vertical longitudinal sectional view taken on the line 5—5 in Fig. 2; Fig. 6 is a vertical sectional view taken on the line 6—6 in Fig. 2; Fig. 7 is a vertical sectional view 50 taken on the line 7—7 in Fig. 2, showing in section the member for swinging the cover

into open position; and Fig. 8 is a vertical sectional view taken on the line 8—8 in Fig. 2, showing the locking catch.

Referring more particularly to the views, 60 I provide a box 10 in which is arranged the usual spring motor 11 operating in conjunction with a vertical rod 12 supporting the usual record tablet 13 and over which operates the usual reproducer 14 carried on 65 the tone arm 15, said reproducer carrying the usual needle or sapphire (not shown). The box 10 is normally closed by a cover 16 and which is preferably mounted to swing at the rear of the box and on its upper edge. 70 The cover is normally held in closed position by a suitable spring-actuated locking catch 17 which, gripping a finger 18 on the cover, holds the same in closed position so that upon actuating the catch the cover will be in 75 unlocked position due to the engagement of the finger 18 with the catch 17.

Mounted to swing on the cover 16 are a plurality of side arms 19 having their lower ends pivoted to similar arms 20 rigidly secured upon a horizontal shaft 21 journaled on the box 10. A weighted pawl 22 is carried by one of the arms 20 and operates over a toothed wheel 23 revolubly supported on the shaft 21 and which, in turn, meshes with 80 a smaller toothed wheel 24 journaled in the box 10 and carried on a shaft 25 to which is rigidly secured a third toothed wheel 26 meshing with a smaller toothed wheel 27 rotatably mounted upon a shaft 28 journaled 85 in the box as shown.

The toothed wheel 27 has a recessed face 29 and in the recess of the face is arranged a friction disk 30 which bears against a substantially circular plate 31 on the shaft 28. 95 The other face of the toothed wheel 27 has a friction disk 32 bearing against the same and abutting against the friction disk is a holding member 33 in the nature of a circular plate 34 and a tubular sleeve 35, said 100 tubular sleeve loosely encircling the shaft 28 with a pin 36 passing diametrically through the sleeve 35 and through a slot 37 in the shaft 28. A portion of the shaft 28 is threaded as indicated by the numeral 38 and arranged thereon is an adjusting member 39 in the nature of a nut and which member bears against one end of an expandible spring 40 encircling the shaft 28 and bearing against the plate 34 of the member 33 105 to hold the plate in frictional contact with the disk 32 and also hold the toothed wheel 110

27 in frictional contact with the disk 30, whereby the disk 30 will also be held in frictional contact with the plate 31.

The shaft 28 carries a substantially circular head 41 through which the shaft extends, said head, however, being rigid on the shaft and provided with a plurality of pins 42 which extend into recessed portions 43 of a coupling member 44 carried on a shaft 45 of the spring motor 11. The recessed portions 43 of the coupling member 44 provide flanges 46 against which the pins 42 are adapted to bear so that rotation of the shaft 28 will result in rotation of the shaft 45 of the spring motor 11.

It will be apparent that when the cover 16 is in raised position on the box and the same is swung downwardly into a closed position the pawl 22, suitably weighted, will engage 20 the teeth on the wheel 23, thus imparting rotation thereto and by having the wheel 23 meshing with the toothed wheel 24 on the shaft 25 and which, in turn, carries the toothed wheel 26 meshing with the wheel 27 on the shaft 28, it will be apparent that 25 rotation will be imparted to the shaft 28 and by providing the coupling between the shaft 28 and the shaft of the spring motor the result of the closing of the cover will be to 30 rotate the shaft of the spring motor and wind up the spring motor so that the spring motor will, in turn, upon unwinding, rotate the shaft or rod 12 and impart rotation to the record tablet 13. When the lid is swung 35 into an open position the pawl 22 will pass freely over the toothed wheel 23 so as not to impart rotation thereto and when the lid or cover is again closed the pawl positively engaging the teeth on the wheel 23 will again 40 rotate the same to repeat the mentioned operation.

As mentioned heretofore, the cover is normally held in closed position by a locking catch 17. In order to cause the cover to automatically open when the locking catch is 45 actuated a weight arm 47 is rigidly carried on the shaft 21 and at its free end carries a suitable weight 48. This weight is of such a nature, size and heaviness that when the 50 cover is released from locked position with the catch it will swing upwardly into an open position. It will be seen that the arms 55 19 are in the nature of rocker arms, the shaft 21 being also in the nature of a rocker shaft and not capable of a complete revolution but simply of a backward and forward turning movement.

It will be readily apparent that if the cover is repeatedly actuated a direct connection between the cover and spring motor 60 would result in the spring being wound up too tightly and in order to obviate this discrepancy the friction disks 30 and 32 are provided and arranged as mentioned heretofore, so that if the cover is repeatedly actuated

the spring motor on being wound to its limit will not be wound up any farther in view of the fact that the connection between the toothed wheel 27 and the shaft 28 is one of friction, the spring 40 being so adjusted 70 as to provide sufficient frictional contact between the toothed wheel, the disk and the shaft that a rotation of the toothed wheel with no rotation of the shaft 28 will only occur when the spring motor has been wound 75 to its limit.

From the foregoing description it will be readily seen that by simply actuating the spring catch 17 the cover will be released to automatically spring into an open position 80 and upon the subsequent return of the cover to closed position the spring motor will be wound up in order that it will impart rotation to the record tablet in the manner set forth. The box 10 is preferably built or constructed with the usual horn or other sounding member (not shown) inside, although it will be understood that the particular mechanism described can be used in connection with various kinds of talking machines 85 or phonographs, and that the relation established between the weighted member on the shaft 21 and the mechanism heretofore described and which connects with the spring motor will result in providing a box having 90 a cover that can be automatically opened and which, when closed, will wind up the spring motor of the talking machine.

Having thus described my invention, I 100 claim:

1. In a talking machine, the combination with a box, of a cover therefor, a motor in the box, a shaft journaled in the box, a connection between the shaft and the cover, driving mechanism connecting the said shaft 105 with the said motor whereby when the said cover is closed on the box the said motor will be wound up, and gravitating means on the shaft for swinging the cover from a closed to an open position.

2. In a talking machine, the combination with a box, of a cover thereon, a motor in the box, a shaft journaled in the box, rocker arms on the shaft and connecting with the cover, means connecting with the rocker arms and the said motor for imparting rotation to the motor when the said cover is 115 swung into closed position on the box, and gravitating means on the shaft for operating the rocker arms to automatically move 120 the cover from a closed to an open position on the box.

3. In a talking machine, the combination with a box, of a cover thereon, a motor in the box, a shaft journaled in the box, rocker arms on the shaft and connecting with the cover, means connecting with the rocker arms and the said motor for imparting rotation to the motor when the said cover is 125 swung into closed position on the box, and a 130

weighted member on the shaft for operating the rocker arms to automatically move the cover from a closed to an open position on the box.

- 5 4. In a talking machine, the combination with a box, of a cover thereon, a motor in the box, a shaft journaled in the box, rocker arms on the shaft and connecting with the cover, means connecting with the rocker 10 arms and the said motor for imparting rotation to the motor when the said cover is swung into closed position on the box, and a weighted member on the shaft for operating the rocker arms to automatically move the 15 cover from a closed to an open position on the box.
5. In combination with a spring motor and a movable member, arms connecting with the movable member, connection between the arms and the spring motor where- 20 by when the said member is moved in one direction the spring motor will be wound up, and a weighted member connecting with the said arms for automatically moving the 25 said member in the opposite direction.
6. In combination with a spring motor

and a movable member, arms connecting with the movable member, connection between the arms and the spring motor where- 30 by when the said member is moved in one direction the spring motor will be wound up, and a weighted member connecting with the said arms for automatically moving the 35 said member in the opposite direction.

7. In combination with a spring motor 35 and a movable member, arms connecting with the movable member, connection between the arms and the spring motor where- 40 by when the said member is moved in one direction the spring motor will be wound up, a weighted member connecting with the 45 said arms for automatically moving the said member in the opposite direction, and means for normally holding the movable member against actuating movement.

In testimony whereof I affix my signature in presence of two witnesses.

JOHN HARRY CLEMMENCY.
